UNITED STATES PATENT OFFICE.

BENJAMIN HARRISON WILSON, OF WILMINGTON, DELAWARE.

STREET-SWEEPING MACHINE.

1,100,808.

Specification of Letters Patent. Patented June 23, 1914.

Application filed April 18, 1913. Serial No. 762,111.

To all whom it may concern:

Be it known that I, BENJAMIN H. WILSON, a citizen of the United States, residing at Wilmington, in the county of Newcastle and State of Delaware, have invented new and useful Improvements in Street-Sweeping Machines, of which the following is a specification.

This invention relates to improvements in street sweeping machines and has particular application to a machine of that type whereby the refuse is gathered up by the machine so that such refuse may be carted away and dumped.

In carrying out the present invention, it is my purpose to provide a street sweeping machine whereby dirt and refuse on the surfaces of roadways will be swept up and thrown into a pan, the latter subsequently delivering the dirt to an elevator so that the refuse may be thrown into the body of the machine and carted away.

It is also my purpose to provide a machine of the class described by means of which the dirt and refuse may be removed from gutters and thrown into the path of the road surface sweeper thereby enabling the gutter and road to be cleaned simultaneously and by a single machine.

Furthermore, I aim to provide a machine of the type set forth which will embrace the desired features of simplicity, efficiency and durability; one which may be operated and maintained at a minimum expense and one wherein the component parts will be so arranged and correlated as to prevent derangement.

With the above and other objects in view, the invention consists in the construction, combination and arrangement of parts hereinafter set forth in and falling within the scope of the claims.

In the accompanying drawings; Figure 1 is a view in side elevation of a street sweeping machine constructed in accordance with the present invention. Fig. 2 is a horizontal sectional view on the line 2—2 of Fig. 1. Fig. 3 is a fragmentary side elevation of the side of the machine opposite from that shown in Fig. 1. Fig. 4 is a rear view of the machine. Fig. 5 is a similar view, parts being shown in section, and Fig. 6 is a fragmentary sectional view through the dust collect-

ing pan and elevator showing the relative arrangement thereof.

Referring now to the accompanying drawings in detail, A designates a wheeled vehicle composed of a box-like body 1 having an open top and provided with a hinged or drop bottom 2. This body 1 is mounted upon a rear axle 3 carrying ground wheels 4, 4, and a forward steering axle equipped with pilot wheels 5. This vehicle may be either horse drawn or motor driven as desired.

Suitably fastened to the opposite sides of the box-like body 1 at the rear end of such body and extending rearwardly thereof are arms 6, 6 having the free end portions thereof inclined downwardly as at 7 and 70 equipped with horizontally alining bearings receiving a horizontal shaft 8 adapted for rotation therein and carrying a sweeper or brush 9 designed, when rotated, to throw the dirt and refuse on the surface of the roadway in a forward direction. In the present instance, the driving mechanism for the horizontal shaft 8 comprises a gear wheel 10 keyed upon one extremity of the shaft and meshing with a similar wheel 11 rotatable about a stub shaft 12 carried by one of the arms 6, said gear wheel 11 having fast upon one face thereof concentrically of the stub shaft 12 a sprocket wheel 13, while a similar wheel 14 is suitably connected with the hub of one of the rear wheels 4 of the vehicle, and over these sprockets 13 and 14 is trained an endless chain 15 by means of which rotary movement is transmitted to the brush 9 in the movement of 90 the vehicle.

Depending from the horizontal portions of the arms 6, 6 and suitably fastened to such arms are bars 16 carrying at their lower extremities a stationary pan 17 contacting with the road surface and disposed in advance of the brush 9 so that as the latter rotates the dirt and refuse will be thrown into the pan 17. Pivotaly connected to the bars 16 and arranged within the pan 17 is 100 a supplemental or auxiliary pan 18 having the front edge thereof equipped with forwardly extending lugs 19.

Suitably fastened to the rear end wall of the body 1 adjacent to the opposite edges of 105 such wall and spaced apart therefrom are

guide rods 20 terminating at their upper extremities above the rear end wall of the body 1 in inwardly and downwardly extending fingers 21, the lower extremities of the guide rods terminating in proximity to the lugs 19 on the pan 18. Slidably mounted upon the guide rods 20, 20 are sleeves or collars 22 provided with depending arms 23 connected at their lower ends to an elevator bucket 24. Extending upwardly from the side walls of the box-like body 1 adjacent to the rear end wall thereof are bearing posts 25 equipped with alining bearings receiving a shaft 26 upon the opposite ends of which are keyed spools 27, 27 each having connected thereto and trained thereabout a cable or rope 28, the free extremities of the cables or ropes 28 being connected to the rear longitudinal edge of the elevator bucket 24 adjacent to the opposite ends of such bucket as at 29, 29. The driving mechanism for the shaft 26 and the drums 27 is preferably automatic and in this embodiment of my invention comprises a sprocket wheel 30 keyed upon one end of the shaft 26, a second sprocket wheel 31 loosely mounted upon the rear axle of the vehicle, and an endless chain 32 trained over such sprocket wheels 30 and 31. The sprocket wheel 31 is adapted for sliding movement upon the rear axle of the vehicle and is provided at one side with teeth 33 adapted to interlock with teeth 34 formed on the adjacent wheel hub. A vertically disposed rod 35 is fulcrumed adjacent to its lower end upon a bracket 36 depending from the bottom of the body 1 and is arranged to one side of the path of movement of the elevator bucket 24 and has the upper and lower ends thereof curved inwardly as at 37 and disposed within such path, while a link rod 38 has one end pivotally connected to the rod 35 and the opposite extremity pivotally connected with the hub of the sprocket wheel 31. By means of this construction, it will be seen that when the elevator bucket 24 gravitates to lowered position and reaches the limit of its path of movement in a downward direction, such bucket will contact with the lower turned end of the rod 35 and thereby swing such rod about its fulcrum with the effect to slide the sprocket wheel 31 so as to interlock the teeth 33 on the hub of such sprocket wheel with the teeth 34 on the hub of the vehicle wheel. Thus, as the vehicle moves forwardly in its path of travel, motion will be imparted to the sprocket wheel 30, through the medium of the chain 32 with the effect to rotate the shaft 26 and drum 27 thereby winding up the cords or cables 28 so that the elevator bucket 24 is raised. When the bucket 24 reaches the limit of its upward movement, the end wall thereof engages the upper inturned end 37 of the rod 35 with the effect to slide the sprocket wheel 31 out of

driving engagement with the respective vehicle wheel thereby relieving the shaft 26 and the drum 27 of the influence of the driving mechanism and permitting the elevator bucket to gravitate to lowered position.

As the brush or sweeper 9 rotates, the refuse in the path of such brush is thrown into the pans 17 and 18 and when the elevator bucket 24 reaches the lower extremity of its path of movement, the forward edge of such bucket contacts with the lugs 19 on the pan 18 and so swings the latter about its pivotal connections with the bars 16 thereby delivering the dirt and refuse within the pan 18 to the bucket 24. Immediately succeeding this operation, the elevator bucket manipulates the rod 35 so as to place the sprocket wheel 31 in driving engagement with the adjacent vehicle wheel thereby enabling the elevator to be carried upwardly, the pan 18 to be restored to initial position and the contents of the elevator bucket deposited within the body 1 of the vehicle.

In order that gutters and the like may be cleaned simultaneously with the cleaning of the surface of the roadway, I employ a second sweeper composed, in the present instance, of a number of brushes 39 carried by the outer ends of cross arms 40 secured to the lower end of a vertical shaft 41 journaled in vertically alining bearings 42 fastened to one side wall of the box-like body 1. Splined upon the shaft 41 between the bearings 42 is a bevel pinion 43 with which meshes a bevel gear 44 fixed to a sprocket wheel journaled upon a stub shaft carried by the respective side wall of the body 1 and over this sprocket wheel carrying the gear 44, and the sprocket wheel fast to the hub of the rear wheel carrying the sprocket wheel 14 is trained an endless chain 45 whereby in the travel of the vehicle movement is imparted to the shaft 41 to rotate the brushes 39 about the axis of such shaft and so throw the dirt and refuse out of the gutter and into the path of the brush 9, as will be readily understood. The shaft 41 is preferably slidably mounted within the bearings 42, 42 and under the control of a system of levers so that the brushes 39 may be elevated and lowered at the will of the operator of the machine.

From the foregoing description taken in connection with the accompanying drawings, the construction, mode of operation and manner of embodying my invention will be readily apparent. It will be seen that I have provided a street sweeping machine wherein the various brushes, the dirt collecting pan and the elevator are all automatic in operation in the travel of the machine thereby enabling the refuse to be delivered to the body of the vehicle and carted away.

While I have herein shown and described one preferred form of my invention by way

of illustration, I desire to have it understood that I do not limit myself to the precise details of construction herein described and delineated, as modification and variation may be made within the scope of the claim without departing from the spirit of the invention.

I claim:

10 In a street sweeping machine, a wheeled vehicle, a pan carried by said vehicle in proximity to the ground and mounted for swinging movement, a sweeper adjacent said pan and rotatable about a horizontal axis, means for rotating said sweeper whereby the refuse will be driven into said pan, an elevator bucket adapted for vertical sliding movement and designed to convey the refuse from said pan into the body of the vehicle, and adapted to tilt said pan whereby the 20 refuse contained therein will be delivered to said bucket, a shaft, spools keyed to said shaft, connections between said spools and

bucket, driving connections between one of the wheels of the vehicle and said shaft, a rod arranged at one side of the path of movement of said bucket and pivoted between its ends for swinging movement and having the opposite ends thereof disposed in the path of movement of the bucket whereby when the bucket reaches its limit of travel in one 25 direction the rod will be swung to one position, while when the bucket is at the opposite end of its path of travel the rod will be swung in the opposite direction, and means operable from said rod for rendering the 30 driving connections between said wheel and shaft active and inactive.

In testimony whereof I affix my signature in presence of two witnesses.

BENJAMIN HARRISON WILSON.
